UNITED STATES PATENT OFFICE.

GEORGE F. NELSON, OF BERKELEY, CALIFORNIA.

VACUUM-PUMP.

1,218,300.

Specification of Letters Patent.

Patented Mar. 6, 1917.

Application filed November 20, 1915. Serial No. 62,498.

To all whom it may concern:

Be it known that I, GEORGE F. NELSON, a citizen of the United States, residing at Berkeley, in the county of Alameda and 5 State of California, have invented new and useful Improvements in Vacuum-Pumps, of which the following is a specification.

The present invention relates to that class of vacuum pumps which depend upon the 10 action of rotary coengaging gear wheels, and the object of the invention is to provide a pump which, first, will develop a higher degree of vacuum than those of this type heretofore employed, and, secondly, so constructed that the cost of manufacture shall 15 be reduced to a minimum.

In the accompanying drawings, Figure 1 is a vertical section of my improved pump; Fig. 2 is a similar section taken at right angles to that shown in Fig. 1; Figs. 3, 4 and 20 5 are horizontal sections on the lines 3—3, 4—4 and 5—5 respectively of Fig. 1.

Referring to the drawing, 1 indicates an annular base having an inner raised portion 2 and a flange 3 around said raised portion. Secured in said base adjacent to said flange are the lower ends of a number, preferably three, of rods 4, the upper ends of which are threaded, as shown at 6. Seated upon 25 said raised portion 2 of the base, within the flange 3, is the lower closed end of a cylindrical container 7. Within said container is a rotary gear-wheel pump 8 comprising a pump head 9, the upper portion 11 of which 30 is cylindrical and which has a cylindrical outwardly extending flange 12, which is seated upon the upper edge of the cylindrical container 7 and has outwardly extending apertured lugs 13, through which 35 extend the upper ends of the threaded rods 4, said pump head being secured to said container 7 by means of slotted screw caps 14, screwed upon the threaded ends of the rods. The lower reduced portion of said head 40 comprises four radially extending portions, and, at the bottom, an outwardly extending flange 45 15. Two diametrically opposite radially extending portions 16, 17 are for the purpose of holding shafts, and the other two 18, 19, 50 are for the purpose of forming walls of conduits. The portion 16 is bored vertically to provide a bearing for a vertical operating shaft 21, the upper end of which carries a grooved pulley 22, by which said shaft can 55 be rotated from any suitable source of power. In the opposite radially extending portion

17 is secured the upper portion of a shaft 23. These shafts 21 and 23 extend in the pump to the same depth below the bottom of the flange 15.

To the bottom of said pump head is secured, by means to be presently described, a gear case 24 having a closed bottom 26 and an open top, closed by the bottom of the pump head, which serves as a cover for the gear case. While I have in the present instance only shown one upper gear case, it is to be understood that they may be a series of any number of upper gear cases, all exactly alike, the bottom of each gear case serving in like manner as the cover for the next lower gear case. In said gear case are two intermeshing gear-wheels 27, 28, of which the wheel 27 is keyed, as shown at 29, on the shaft 21, while the other gear-wheel 28 is loose on the shaft 23. Immediately below the first gear case I have shown, in this case, the lowermost gear case 31, there being shown only two gear cases altogether, although I may use any number. In this case also there are a pair of gear-wheels 32, 33, one 32 keyed to the shaft 21 and the other loose on the shaft 23. All of these gear cases are secured to the pump head by means of screws 34, 36. The head of the screw 34 bears against the bottom of the lowermost gear case and said screw 36 extends through apertures in lugs 37, 38 in the two gear cases and the top of the screw is screwed into a threaded socket in the radially extending portion 18. In like manner the head of the screw 34 bears against the under side of a lug 39, and the screw itself passes through apertures in said lug and in a lug 41 and said screw is screwed into a threaded socket in the opposite radially extending portions 19. By means of these two screws the gear cases and the pump head are held tightly together.

In said radially extending portion 18 there is formed a conduit 43 which leads radially inward and then in the top of the pump head downwardly into the middle of one side of the cavity of the first gear case and into the inlet end of said conduit is screwed the inner end of an outwardly tapering tube 44 upon the outer end of which is slipped a rubber tube, not shown, which is connected with the chamber in which a vacuum is to be formed. Also extending through the oppositely radially extending portion 19 is a conduit 46 discharging at a side of said radially extending portion and therefore with-

in the cylindrical container above the level of oil, as hereinafter described. In the bottom of the upper gear case, and of succeeding gear cases of the series if more than one upper gear case is used, is formed a transverse conduit 47, one end of which communicates, as shown at 48, with the interior of said gear case, while the other end, at the other side of the gear case, opens through the bottom of the gear case and therefore communicates with the interior of the next succeeding gear case below it, since, as already stated, the bottom of each gear case forms a cover for the next succeeding gear case.

In the upper portion of the lug 39 is formed a channel 49 leading from the interior of the lower gear case and communicating with a hole 51 formed through the corresponding lug 41 of the upper gear case, which in turn communicates with the discharge conduit 46, leading, as heretofore stated, to the interior of the container.

Leading to the bearing for the rotating shaft 21 are lubricating conduits 52. Thereby not only is the bearing lubricated, but the oil forms a seal around the shaft preventing the leakage of air along said shaft to the first gear case.

The foregoing being the construction of the apparatus, the following is the method of use. Oil is supplied to the receptacle until it is at a level sufficiently above the lubricating conduits 52. The shaft 21 being now rotated, and supposing that the gear-wheels rotate in the direction of the arrow, as shown in Fig. 4, then, since the gear teeth move practically in contact with the gear case, the oil in the cavity between the sides of the gear-wheels from which they rotate is carried by the teeth of said gear-wheels away from the cavity on that side, and the outward motion of the oil therefore produces a suction of air which flows down from the chamber to be exhausted through the inlet conduit 43 and this air is carried with the oil around the gear-wheels to the opposite side thereof. This effect is produced at the same time by each pair of gear-wheels, so that the suction causes the air to pass down into the transverse conduit 47 by said conduit to the lower gear case. When it reaches the lowermost gear case it is expelled into the channel 49 in the lug 39 of said case, which channel communicates with the atmosphere, as hereinbefore explained.

To insure that no air can escape between the teeth of the lowermost pair of gear-wheels where they mesh with each other, I provide two small holes 56 in the bottom of the lowermost gear case, which admit oil, and since the container is at atmospheric pressure, and the interior of the lowermost gear case is nearly at the pressure of the chamber which is being exhausted, the oil

rushes in through these small holes, and is carried around by the teeth of the gear-wheels until they mesh with each other, and this absolutely insures that no air can pass from the discharge side of the pair of gear-wheels to the inlet side thereof. Furthermore it insures that there will be in the discharge conduit an almost continuous column of oil broken at intervals by columns of air, which latter columns become more and more minute as the pumping progresses, the air being discharged from the top of the discharge conduit into the cylindrical container, from which it escapes to the atmosphere by a hole 57 through the pump head, the oil returning by gravity to the container.

It will be observed that all portions of the inlet conduit for the air lead continuously downward, and therefore there is no opportunity for the oil to form a trap preventing its downward flow.

I claim:—

1. The combination of a liquid container, a pump secured therein comprising a pump head having exhaust and discharge conduits, a series of gear cases secured to said pump head, a pair of intermeshing gear-wheels in each gear case, a fixed shaft carried by the pump head and on which a gear-wheel of each pair is loosely mounted, a rotary shaft having a bearing in the pump head and to which the other gear-wheel of each pair is secured, each gear case having a transverse conduit leading from the space between the gear-wheels on one side of the gear case to the space between the gear-wheels on the other side of the next lower gear case, the lowermost gear case having an entrance for liquid.

2. The combination of a liquid container, a pump secured therein comprising a pump head having exhaust and discharge conduits, a series of gear cases secured to said pump head, a pair of intermeshing gear-wheels in each gear case, a fixed shaft carried by the pump head and on which a gear-wheel of each pair is loosely mounted, a rotary shaft having a bearing in the pump head and to which the other gear-wheel of each pair is secured, each gear case having a transverse conduit leading from the space between the gear wheels on one side of the gear case to the space between the gear-wheels on the other side of the next lower gear case, the lowermost gear case having passages through its bottom for pumping up liquid, the pump head having an aperture therethrough for the escape of air from the container to the atmosphere.

3. The combination of a liquid container, a pump secured therein comprising a pump head having exhaust and discharge conduits, a series of gear cases secured to said pump head, a pair of intermeshing gear-wheels in

each gear case, a fixed shaft carried by the pump head and on which a gear-wheel of each pair is loosely mounted, a rotary shaft having a bearing in the pump head and to which the other gear-wheel of each pair is secured, each gear case having a transverse conduit leading from the space between the gear-wheels on one side of the gear case to the space between the gear wheels on the other side of the next lower gear case, the lowermost gear case having a passage through its bottom for pumping up liquid, the pump head having a lubricating conduit from the interior of the container to the bearing for the rotary shaft in the pump head.

4. The combination of a liquid container, a pump secured thereto comprising a pump head having exhaust and discharge conduits, a series of gear cases secured to said pump head, a pair of intermeshing gear-wheels in each gear case, a fixed shaft carried by the pump head and on which a gear-wheel of

each pair is loosely mounted, a rotary shaft having a bearing in the pump head and to which the other gear-wheel of each pair is secured, each gear case having a transverse conduit leading from the space between the gear-wheels on one side of the gear case to the space between the gear-wheels on the other side of the next lower gear case, the lowermost gear case having a passage through its bottom for pumping up liquid, the pump head having a lubricating conduit from the interior of the container to the bearing for the rotary shaft in the pump head, and also having an aperture therethrough for the escape of air from the container to the atmosphere.

In testimony whereof I have hereunto set my hand in the presence of two subscribing witnesses.

GEORGE F. NELSON.
